United States Patent Office

Des. 181,739

Patented Dec. 17, 1957

181,739

FOOTBALL GAME TABLE OR SIMILAR ARTICLE

Marcel Lucca, Geneva, Switzerland

Application December 7, 1956, Serial No. 44,104

Term of patent 7 years

(Cl. D34—3)

The single figure is a perspective view of a football game table or similar article, showing my design.

The opposite side and end, not shown, have substantially the same appearance.

I claim:

The ornamental design for a football game table or similar article, as shown and described.
